UNITED STATES PATENT OFFICE.

HERMANN WEINACKER, OF PROVIDENCE, RHODE ISLAND, ASSIGNOR, BY MESNE ASSIGNMENTS, TO GENERAL CHAIN COMPANY, OF PROVIDENCE, RHODE ISLAND, A CORPORATION OF MASSACHUSETTS.

CHAIN-MAKING MACHINE.

1,340,639.

Specification of Letters Patent.

Patented May 18, 1920.

Application filed November 20, 1917. Serial No. 203,017.

To all whom it may concern:

Be it known that I, HERMANN WEINACKER, a subject of the Emperor of Germany, and resident of the city of Providence, in the 5 county of Providence and State of Rhode Island, have invented certain new and useful Improvements in Chain-Making Machines, of which the following is a specification.

10 This invention relates to machines for automatically making chain of the class more particularly adapted for personal wear.

The object of this invention is to provide 15 such a machine adapted to continuously and automatically make chain from wire, and also to so construct the machine that it may be caused to vary the length of the links at intervals along the length of the chain, all 20 of which mechanism and its operation are hereinafter described.

With these and other objects in view, the 25 invention consists of certain novel features of construction, as will be more fully described, and particularly pointed out in the appended claims.

In the accompanying drawings:

Figure 1— is a front elevation of my improved machine.

30 Fig. 2— is an enlarged view partially in section showing a group of the wire-feeding mechanism.

Fig. 3— is a plan view of the machine and showing that portion around the link-forming head broken away to better illustrate the 35 action of the machine.

Fig. 4— is a plan view in section illustrating the mechanism for operating the link-closing fingers.

40 Fig. 5— is a side elevation showing a general arrangement of the mechanism which operates the link-closing fingers.

Fig. 6— is a detail showing the link-opening jaws and the die which closes the ends of 45 the link.

Fig. 7— is a sectional side elevation of the link-forming head.

Fig. 8— is a top view of the link-forming head showing the same rotated at 90° and 50 in position to permit the next advancing feed of the wire to pass through the link previously formed.

Fig. 9— is an enlarged detail illustrating

the means for locking the head in its down position while the bending jaws are being 55 actuated to perform their functions.

Fig. 10— is a detail illustrating the cam, its yoke and lever by means of which the link-forming head is rotated its 90°.

Fig. 11— is a detail in perspective of the 60 link-supporting fork which serves to support the lower end of the link while being forced by the forming tool down between the bending jaws.

Fig. 12— is a side elevation partly in section illustrating the mechanism for controlling the position and the operation of the 65 link-forming arbor.

Fig. 13— is a perspective view showing the 70 large link as being formed about the corresponding portion of the arbor.

Fig. 14— is the same as Fig. 13 but showing the small link as being formed about its portion of the arbor.

Fig. 15— is a perspective view showing 75 the support for the outer end of the wire.

Fig. 16— is a view looking at the end of the link-forming arbor showing the same as having descended sufficiently to engage and bind the link on the wire, to prevent 80 lateral motion of the link while the forming head releases the chain and is rotated 90°.

Fig. 17— shows the link-forming jaws as having been rotated 90° and now in position to permit the length of wire to be 85 folded into U-shape by being forced between its jaws.

Fig. 18— is a detail showing short sections of chains having different combinations of large and small links. 90

Referring to the drawings, 20 designates the bed of the machine on which all of the mechanism is supported, the same being mounted on legs 21. On this bed are two main bearings 22 in which the main cam shaft 23 is mounted to be driven through the pulleys 24. An auxiliary cam shaft 25 receives its motion from the main through gears 26, 27 and 28. The ratio of the driving speeds between these shafts may be varied at will, to produce any desired variation in the relative formation of the links. That now to be described is for forming chain having alternate large and small links. 95

Forward of the main shaft is mounted a 100 rock shaft 29 on which most of the cam

levers operated from the main shaft are pivoted.

The wire 19 is fed to the machine from the reel 31, through the reciprocating feed block 30 and under the loose jam plate 33, see Fig. 2, which is caused to bite the wire under pressure of the roll 34, from the cam 35 through the lever arms 36 and the plunger 37. This feed block is advanced by the cam 38 through the lever 39 pivoted at 40 by engagement of its lower end 41 therewith, the block being returned under pressure of the spring 42. The extent of advance of this block being due to the extent 15 of stroke of this lever, the length of which is controlled by the positioning of the limit screw 43 which limits the backward movement of this lever. After the wire has been advanced a length it is bound by the plate 20 44 under pressure of the pin 45 from the cam 46 through the lever 47 and plunger 48 so as to prevent it from moving backward when the feed block returns for another bite. This wire extends over the cutter anvil 49 and over the forming head, with 25 its extremity resting in the support 50.

When the short length of wire is being fed for the purpose of making a small link *a*, the head 52 of the stop screw, see Fig. 2, is raised into the path of movement of the nuts 53 on the threaded shaft 43, by means 30 of the cam 54, see Fig. 3, through the rod 55, lever 56 and plunger 57, thereby shortening up the return stroke of the actuating arm 39; and when the large link *b* is desired this stop head 52 is dropped permitting the nuts to return their full stroke against the abutment 58. When the short 35 length of wire has been fed, its extremity extends a predetermined distance beyond the center line of the forming head and, therefore, in order that the ends of the link shall be central above the arbor this wire must be severed an equal distance on the opposite 40 side of this center line. Therefore in order to accomplish this I have provided a cutter 59 which is adapted to be moved longitudinally along the length of the wire, from the severing point 60 of the long link, to the 45 severing point 61 of the short link, see Fig. 7, which longitudinal movement is accomplished by action of the cam 62 through the lever arm 63 pivoted at 64. On the plunger 65 is mounted the roll 66, which acts upon 50 the inclined edge 67 of the carrier 68 causing this carrier in which the cutter 59 is mounted, to slide longitudinally to the right on suitable bearings to move the cutter over the notch 61, and when this plunger 65 is 55 released it rises under action of its spring 69 permitting this carrier under action of its spring 70, to return and bring the cutter back over the notch 60. The cutter itself is carried in the plunger 80 to reciprocate vertically in the longitudinally movable carrier 60

68 so that when in the advanced position for cutting short lengths at the point 61 it is actuated by the cam 81 on the shaft 23, through the lever 82 to be forced downward to sever the wire at this point; and when 70 it returns to the point 60 it is then operated by the cam 83, on shaft 25, through the lever 84. As soon as released by either of these levers the plunger rises by action of the spring 85 to raise the cutter from severing 75 position.

The severed length of wire is now engaged by the forming arbor 86, see Figs. 12, 13 and 14, and by it forced downward between the open wire-bending jaws 87, see 80 Fig. 7, the operation of which is hereinafter described. The action of this arbor is as follows: The arbor itself is slidably mounted in the sleeve 88, which in turn is mounted in the reciprocating head 89 85 adapted to slide vertically in the bearing 90. When the small link is to be formed, then the lever 91, under action of the cam 92, serves to move this arbor to the right, bringing its reduced or smaller portion 93 90 in line with the wire. The stop 99 is now raised by the cam 105 through the member 96 and rock arm 97, to engage the collar 100 and retain the arbor in the desired longitudinal position, at which time the cam 94 through the lever 95 and head 89 causes the arbor to descend and lightly engage the link in its under groove 155 as illustrated in Fig. 16, to prevent the same from moving out of position while the jaws 87 of the forming head release the chain and rotate 90° into the position illustrated in Fig. 17 at which time the cam 103 through the lever 104 completes the downward stroke of the arbor to bend the wire into U-shape between 105 the jaws 87.

The upper ends of the U-shaped link are now partially closed together over the upper edge of the arbor by mechanism hereinafter described. This arbor is withdrawn endwise from the link just formed by another rotation of cam 92 when the head is permitted to rise to its normal position under action of the spring 106 ready for another operation. When the long link is being formed the arbor in its head 89 is forced down an increased distance by means of the larger cam 107 on the shaft 25 through the lever 108.

After the length of wire has been cut and forced down into U-shape between the jaws 87, it is found necessary to provide an auxiliary means for a preliminary closing of these ends over the upper edge of the arbor. To accomplish this in a simple and effective 125 way I have provided a pair of fingers 109 mounted in spring jaws 110, to stand normally apart.

The outer end of this spring jaw member is provided with a T-head 111 through 130

which is passed a stop screw 112 on which is mounted stop collars 113 and 114. This spring jaw member is mounted in the sleeve 115 adapted to slide endways in the bearing 116, said sleeve being normally held in out position by means of spring 117.

In order to operate these fingers 109 I have provided a cam 118, which acting through the member 119 and rock arm 120 10 serves to move the fork end 121 of this arm upward and also forward to first advance these fingers into position to straddle the projecting ends of the open link, then the collar 111 brings up against the stop nuts 113 after which the lever continuing its forward motion advances the sleeve to move its small screws 122 into engagement with the beveled edges of the jaws 110, thereby closing the jaws and causing the fingers 109 15 to engage and partially close the free ends of the link over the upper edge of the arbor. It is only necessary now for the die 123 to be forced downward, under action of its cam 124, lever 125 and plunger 126 for fully 20 closing and causing the ends to abut squarely one against the other.

In order to manipulate the different links and assist in forming them and linking them one with the other successively, I have provided, what I term, a "link-forming head" 30 the construction and operation of which are best illustrated in Fig. 7. The body portion of the head comprises essentially a base plate 127 having two spaced-apart side walls 128, the whole being supported on a tubular shaft 129 which extends down through the bed 20 of the machine. Between these side walls are mounted the jaws 87 on pivot pins 130, which jaws are actuated to close on the 35 wire link by a T-head member 131, which head member is also provided with a hollow shaft 132 extending through shaft 129. Through the center of this T-head shaft extends an inner tubular shaft 133, the 40 upper end of which supports the link-supporting fork 134, which latter is shown on an enlarged scale in Fig. 11. The branches of this fork are grooved on their upper ends to receive the wire when forced down by the 45 arbor into the jaws to determine the depth to which the U-shaped link member shall be forced therein, the elevation of this fork being controlled by the cam 135 through the member 136, lever arm 137 whose outer arm 50 50 engages this tubular shaft, so that when the small link is to be formed this fork is held in its up position and when the large link is to be formed it is held in its down position. The chain 51 as formed hangs 55 down through the center of this inner shaft as indicated by the dot-dash lines in this figure. The jaws 87 are opened and closed at the proper time by means of the cam 139, 60 see Fig. 1, acting through the member 140 and rock arm 141, its outer end 142 engaging

the lower end of the tubular shaft 132, whereby raising this shaft causes the T-head acting through the engaging points 143 to close the jaws and when released by the cam, the jaws are opened through the tension 70 springs 144.

After the ends of the link have been closed over the arbor by means of the die 123, above described, the arbor is then withdrawn endwise and the head is rotated 90° 75 by the action of the cams 145 and 146 on shaft 23 through the fork 147 and slide bar 148 which has a depending pin 149 engaging the slotted lever 150 secured to the forming-head shaft 129, thereby bringing the head 80 into the position illustrated in Fig. 8, into which position the whole head is now raised through the action of the above-mentioned cam 139. The head is now supported in this up position by cam 151, member 152, 85 see Fig. 1, rock arm 153 whose outer end 154 engages the end of the tubular shaft 129 so that the link just formed will be in line and position to permit the next advancing length of wire to pass therethrough after which the 90 lever 141 under action of its cam permits the T-head to drop to open the jaws 87 after which the head returns to its seat, the arbor descends causing its grooved-out under portion 155 to engage the link to prevent lateral 95 movement thereof. The length of the wire is then severed by the cutter, the head is rotated 90° back to the position illustrated in Fig. 7, and the arbor descends to bend the wire, after which the ends are closed over 100 the arbor, all as described.

In order to insure the head returning to its seat when rotated back into the position illustrated in Fig. 7, and prevent it from subsequently rising, I have provided a pair 105 of over-hanging lips 156, see Figs. 8 and 9, which engage pins 170 on the head member, locking the head member securely in position against rising while undergoing the wire-bending operations.

The wire-supporting member 50 is made with a V-shaped groove 171, see Fig. 15, which is open on its upper edge, whereby the extremity of the wire is supported, but which extremity, owing to the upper side of 115 the V groove, is permitted to tip upward clear of its support upon being engaged by its arbor and forced down between the jaws.

The general operation of my improved chain-making machine for making links of 120 different lengths is as follows:

The wire is fed in from the reel 31 by the wire-feeding device. When a length for a large link is to be fed the feed lever 39 is permitted to take its long stroke to advance 125 a length of wire sufficient for this link. The larger portion 102 of the arbor is then positioned to retain the link, the cutter 59 is then moved back to sever the wire at the point 60, the arbor descends to bend the 130

wire into the U-shape whose ends are subsequently closed thereover in the manner above described, the arbor is withdrawn endwise from the link and raised for the 5 next operation, which in this particular instance is the forming of the small link. After the stop 52 is raised to prevent the feed lever from returning its maximum stroke the short length of wire is fed. The 10 arbor is now withdrawn slightly to bring the small size link portion 93 over the wire, the cutter 59 is now advanced along the length of the arm to sever the wire at the point 61, so that the ends will be equally 15 distanced on opposite sides of the center line through the link-forming jaws. The rest of the operations are then performed, all as above described; first a long and then a short link being formed, which arrangement 20 of links is controlled by the ratio of the gearing between the main and the auxiliary cam shaft.

By the control of the ratio of revolutions of these two shafts any desired combination 25 of long and short links may be obtained.

The foregoing description is directed solely toward the construction illustrated, but I desire it to be understood that I reserve the privilege of resorting to all the 30 mechanical changes to which the device is susceptible, the invention being defined and limited only by the terms of the appended claims.

I claim:

35 1. In a chain machine, a link-forming head, means for feeding the wire to said head, wire severing means, means for shifting said severing means for cutting the wire into predetermined lengths differing 40 from the length of wire bed, and means for bending the different lengths into links of different sizes.

45 2. In a chain machine, a link-forming head, means for feeding wire to said head, a cutter, means for automatically moving said cutter along the length of the wire to sever it into different predetermined lengths, and means for bending said lengths into links of different sizes.

50 3. In a chain machine, a link-forming head, a pair of bending jaws in said head, means for advancing different lengths of wire to said jaws, a cutter, means for causing said cutter to intermittently sever the wire into lengths differing from that fed by the wire feed, and means for bending the different lengths into links of different sizes.

60 4. In a chain machine, a link-forming head, a pair of bending jaws in said head, means for advancing different lengths of wire to said jaws, a cutter, means for causing said cutter to intermittently sever the wire into lengths differing from that fed by the wire feed, link-forming arbors of different sizes, means for selecting and positioning the

different sized arbors corresponding to the size of link to be formed, and means for forming the different links thereover.

5. In a chain machine, a link-forming head, a pair of bending jaws in said head, 70 means for advancing different lengths of wire to said jaws, a cutter, means for causing said cutter to intermittently sever the wire into lengths differing from that fed by the wire feed, means for bending the different lengths into links of different sizes, 75 link-forming arbors of different sizes, means for selecting and positioning the different sized arbors corresponding to the size of link to be formed, means for forming the 80 different links thereover, and means for imparting to the different arbors the different strokes required for forming the links of different sizes thereover.

6. In a chain machine, a holder through 85 which the chain passes as formed, a pair of link-bending jaws in said holder, means for intermittently feeding different lengths of wire to said holder through the next previously formed link, a cutter, means for automatically moving said cutter longitudinally along the wire, means for operating said cutter, and means for presenting different sizes of an arbor around which each length is bent into links of different shapes. 90

7. In a chain machine, a holder through 95 which the chain passes as formed, a pair of link-bending jaws in said holder, means for feeding different lengths of wire to said jaws, means for severing the wire into pre-determined lengths, means for automatically 100 presenting arbors of different sizes corresponding to the length of wire cut, and means for causing said jaws to bend said lengths into link form about said different 105 arbors.

8. In a chain machine, a holder through 110 which the chain passes as formed, a pair of link-bending jaws in said holder, means for intermittently adjusting the wire feed to advance different lengths of wire to said 115 holder, a cutter, means including said cutter for severing the wire into predetermined lengths, and means for successively presenting said lengths to said jaws to be bent into links of different sizes.

9. In a chain machine, a link-forming head, a pair of bending jaws in said head, 120 means for feeding different lengths of wire to said jaws, a bottom support between said jaws for the loop end of the link, means for forcing the wire into said jaws against said support, and means for automatically moving said support to accommodate links of different sizes. 125

10. In a chain machine, a link-forming head, a pair of bending jaws in said head, means for alternately advancing different lengths of wire to said jaws, a cutter, means for causing said cutter to intermittently 130

sever the wire into lengths differing from that fed by the stroke of the wire feed, link-forming arbors of different sizes corresponding to the size of links to be formed, 5 means for first advancing said arbor to engage and retain the link next previously formed, means for then positioning said jaws for the bending operation, and means for subsequently completing the bending 10 stroke of said arbor to form the links there-over.

11. In a machine, a link-forming head, a pair of wire-bending jaws in said head, means for alternately feeding different lengths of 15 wire to said jaws, a cutter, means for adjusting said cutter to sever the wire into different lengths irrespective of the length of the wire feed, a bottom support between said jaws for the loop end of the link, an arbor, means 20 for moving the arbor to force the bight of the wire into said jaws against said support, means for varying the bending stroke of the arbor, and means for moving said support to accommodate links of different sizes.

25 12. In an automatic chain-making machine, wire-bending means, means for severing the wire as fed into different predetermined lengths, means for forming and connecting links of different sizes from the

different lengths of wire, means whereby said 30 link-forming means may be adjusted to form different combinations of the different sized links, and means whereby these combinations may be varied.

13. In an automatic chain-forming machine, means for feeding and severing wire into different lengths, means for shaping the wire of different lengths into links of different sizes and connecting together said links, means including cams operated by a main 35 and an auxiliary cam shaft for operating said link-forming mechanism, and means whereby the speed ratio of said shafts may be varied to provide different combinations of link formations.

45 14. In a chain machine, a link-forming head, a pair of bending jaws in said head, means for feeding different lengths of wire to said jaws, means for forcing the wire into said jaws, and means for automatically 50 adjusting said jaws to accommodate links of different sizes.

In testimony whereof I affix my signature in presence of a witness.

HERMANN WEINACKER.

Witness:

HOWARD E. BARLOW.
